DESIGN FOR A RECORDER CHART HUB

Norman J. Smith, Medfield, Mass., assignor to
Crosby Steam Gage & Valve Company, Boston,
Mass., a corporation of Massachusetts

Application March 25, 1939, Serial No. 83,823

Term of patent 14 years

To all whom it may concern:

Be it known that I, Norman J. Smith, a citizen of the United States, residing at Medfield, in the county of Norfolk, Commonwealth of Massachusetts, have invented a new, original, and ornamental Design for a Recorder Chart Hub, of which the following is a specification, reference being had to the accompanying drawing, forming part thereof,

Fig. 1 is a perspective view of a recorder chart hub showing my new design; and Fig. 2 is a view of the recorder chart hub taken from the opposite side.

I claim:

The ornamental design for a recorder chart hub, substantially as shown.

NORMAN J. SMITH.
